UNITED STATES PATENT OFFICE.

ALBERT HUPP, OF WASHINGTON, DISTRICT OF COLUMBIA, ASSIGNEE TO HUPP AUTOMATIC MAIL EXCHANGE COMPANY, OF WASHINGTON, DISTRICT OF COLUMBIA, A CORPORATION OF DELAWARE.

RAILWAY MAIL-CRANE.

1,354,559.

Specification of Letters Patent.

Patented Oct. 5, 1920.

Application filed January 25, 1915. Serial No. 4,239.

To all whom it may concern:

Be it known that I, ALBERT HUPP, a citizen of the United States of America, and resident of Washington, in the District of Columbia, have invented certain new and useful Improvements in Railway Mail-Cranes, of which the following is a specification.

This invention relates to mail exchange apparatus and more particularly to the station crane for supporting the mail bag in position to be delivered to a passing train.

One of the objects of the invention is to provide an improved construction in which the bag supporting arms are held in position to deliver a bag by means which is automatically released when the bag is delivered and permits the arms to be swung away from the track. A further object is to provide a crane in which the parts are so arranged that the swinging of the arms away from the track is effected by gravity and in which the parts are so arranged that there is always a tendency for the arms to be swung away, this tendency being overcome by a latch which is controlled by the mail bag so that upon the delivery of the bag the latch will be automatically released and the force of gravity permitted to operate on the parts to swing the arms.

Other objects and the features of novelty will be apparent from the following description, taken in connection with the accompanying drawings, in which:

35 Figure 1 is an elevation of a mail receiving trough and the mail crane supported on a suitable framework above the trough;

Fig. 2 is an enlarged plan view of the mail crane;

40 Fig. 3 is an enlarged sectional view on the line 3—3 of Fig. 1;

Fig. 4 is a longitudinal section of the part shown in Fig. 3;

Fig. 5 is a section on the line 5—5 of Fig. 3;

45 Fig. 6 is a vertical section on the line 6—6 of Fig. 2;

Fig. 7 is a bottom plan of the part shown in Fig. 6, certain parts being shown in section.

50 Referring to the drawings, 10 indicates a mail receiving trough which is specially adapted for use in connection with that character of mail exchange system described

in my Reissue Patent No. 13,716, granted April 21, 1914. Arranged on a platform 11, above the trough 10, is a hollow post 12 in which a vertical tube 13 is rotatably supported and also adapted to move up and down. The post 12 has a bottom flange 14 and is also supported by means of braces 15. At the upper end of the tube 13, there is a split bracket 16 which is clamped to the tube 13 and one-half of which carries the cover plate 17 closing the upper end of the tube. The bracket 16 has secured therein a tubular arm 18. A split bracket 19 is also secured to the tube 13 and carries a tubular arm 20.

At the upper end of the post 12, there is a flange or cam track 21 having the inclined portion 22 on the side of the post adjacent the railway track and also an inclined portion 23 on the opposite side of the post. The bracket 19 is provided with downwardly extending arms 24 which carry a roller 25, this roller being arranged to engage the track 21. When the arms 18 and 20 are in position to deliver a bag to a passing train the roller 25 is adjacent to the upper end or peak of the inclined part 22 of the cam track, as shown in Fig. 3. It will be understood that the roller 25 may be in the position shown in Fig. 3 or in a similar position on the opposite side of the peak of the incline. When the parts are in this position the action of gravity on the tube 13 and the parts supported thereby tends to cause the roller 25 to run down the incline 22 and thereby swing the arms 18 and 20 away from the railway track. When the roller 25 descends the incline 22, the parts gain such momentum that it is desirable to stop the rotation and thus prevent the arms from swinging clear around and starting up the opposite side of the incline 22. For the purpose of stopping the rotation, the incline 23 is provided. From Figs. 3 and 4, it will be evident that the incline 23 is lower than the incline 22, and in the operation of the mechanism it has been found that the tube 13 will rotate a sufficient distance to cause the roller 25 to run up the incline 23 and then run back a short distance and come to rest with the arms 18 and 20 arranged substantially parallel with the railway track or directed at a slight angle to the rear of the axis of the post 12.

From the foregoing, it will be evident that with the parts in the position shown in Figs. 3 and 4, it is necessary to have some means for locking the tube 13 to the post 12 in order to hold the arms 18 and 20 in position to deliver a bag to a passing train. In the embodiment of the invention shown, this holding means consists of a latch 26 having a substantially chisel-shaped edge 27 which is adapted to engage an opening 27 in the post 12. The latch 26 is arranged in a transverse tube 28 secured in the tube 13 and a spring 29 normally tends to withdraw the latch from the opening 27. A lever 30 pivoted in the tube 13 at 31 has its lower end in engagement with the latch 26 as shown in Fig. 4. The upper end of the lever 30 has pivotally connected therewith a rod 32 arranged in the arm 18. The outer end of the rod 32 is telescoped with a member 33 which is slidably arranged in the outer end of the arm 18. The rod 32 has secured thereon a collar 34 and between this collar and the member 33 there is a spring 35.

A collar 36 is clamped on the outer end of the arm 18 and has pivoted thereto the bag grippers 37 and 38. The forward ends of the grippers 37 and 38 are arranged substantially in alignment with the forward end of the member 33 when the parts are in the position shown in Figs. 6 and 7. The rearward ends of the grippers 37 and 38 are provided with eyes through which a rod 39 passes. A spring 40 is coiled on the rod 39 and normally forces the rearward ends of the grippers apart so as to effect a pinching movement of the forward ends of the grippers. The movement of the grippers 40 under the influence of the spring 40 may be limited in any suitable manner as by means of the adjustable stop screws 41 which are carried by a box 42 arranged over the grippers and adapted to protect the mechanism 45 from the weather. The box 42 is supported by the tube 18 and by the collar 36 and is secured to the latter by a suitable bolt 43.

In order to provide for opening the grippers 36 and 37, so as to permit attachment 50 of a mail bag, I have provided a rotatable member 44 which is supported by the tube 18 and the box 42 and is connected with the grippers 37 and 38 by means of links 45 and 46 respectively. The upper part 47 of the member 44 is angular in shape to provide for the attachment of a wrench thereto by means of which the member 44 may be turned so as to draw the rearward ends of the grippers 37 and 38 toward each other. It will be evident from Fig. 7 that the links 45 and 46 are so curved as to permit the member 44 to rotate slightly more than 90° so as to secure the grippers in the open position by the toggle action on the links 45 and 46.

In Fig. 1, a bag 48 is shown in position to be delivered to a passing train and it will be noted that in order to insert the upper end of the bag between the grippers 37 and 38, the member 33 must be moved 70 toward the tube 13. When the member 33 is thus moved the bag is inserted between the grippers, and the member 44 rotated to cause the grippers to seize the bag. The movement of the member 33 toward the tube 75 13 compresses the spring 35, because the rod 32 is normally held against rearward movement by the engagement of the end of the latch 26 with the inner surface of the post 12. The spring 35 is much stronger 80 than the spring 29 and therefore when the former is compressed by moving the member 33 the latch 26 will be forced into the opening 27 when the tube 13 is rotated to bring the latch in alignment with the opening. When the bag is withdrawn from the grippers 37 and 38, the spring 35 will force the member 33 outward to the position shown in Figs. 6 and 7, and this will release the tension on the spring 35 and permit the spring 29 to withdraw the latch 26 from the opening 27, and thereby release the tube 13 and permit the latter to rotate.

The arm 20 has secured thereon a substantially horizontal plate 49 which is provided with a groove or depression 50 which is arranged substantially at right angles to the arm 20. The plate 49 is also provided with openings 51 for the passage of water therethrough. From Fig. 1, it will be evident that the groove 50 forms a seat for the bottom of the mail bag 48 and wherein the bag will be securely held against displacement by the wind or other causes, when the bag is comparatively heavy. In the case of 100 a light bag, however, the bottom might be blown out of position on the plate 49 and for the purpose of securing the bottom of such a bag I have provided a guard 52 which is pivoted to the plate 49 and has 105 arms 53 on the underside of the plate to which springs 54 are attached. The springs 54 tend to hold the guard 52 against the plate 49 for the purpose of gripping the lower part of the bag. At the same time 110 the springs permit the guard 52 to be lifted so that a bag may be inserted.

For the purpose of forming a more rigid construction a tie rod 55 connects the arms 18 and 20 and is preferably provided with 115 a turn buckle 56 by means of which the rod may be tightened.

In the operation of the crane, the normal, inoperative position, of the arms 18 and 20 is over the platform 11 and the bag 125 48 is placed on the plate 49 and the grippers 37 and 38 opened in the manner above described, and then the member 33 pushed back and the grippers closed on the neck of the bag. The arms 18 and 20 are then 130

swung around to the position shown in Fig. 1, the latch 26 entering the opening 27 in the post and securing the parts in this position. When the bag is removed from the 5 arms 18 and 20 by a passing train, the member 33 is returned to the position shown in Figs. 6 and 7, and the latch 26 withdrawn from the opening 27. This permits the roller 25 to run down the incline 22 and 10 thus cause the tube 13 and the arms 18 and 20 to swing to the inoperative position. For the purpose of protecting the cam track 21 and the roller 25 from the weather a shield or apron 57 is provided on the bracket 19.

15 Having thus described my invention, what I claim is:

1. In a mail crane, the combination of a post, a tube supported thereby, the axes of the tube and post being in alinement, vertically spaced bag supporting arms secured 20 on said tube, a latch coating with said post and the lower part of said tube to hold the latter in position to deliver a bag, a member at the outer end of the upper of said 25 arms arranged to be moved when the bag is attached to said arm, and means arranged in said arm and said tube and including spring-separated telescopic parts for operatively connecting said member and said 30 latch.

2. In a mail crane, the combination of a post, a tube rotatably supported thereby, a latch carried by said tube and adapted to engage said post to lock the parts together, a spring for releasing said latch, a lever 35 pivotally arranged in said tube and engaging said latch, a bag supporting arm secured to said post, a slideable member carried by said arm at the outer end thereof, and a yieldable connection between said slideable member and said lever.

3. In a mail crane, the combination of a bag supporting arm, a rotatably supported member on which said arm is secured, a pair 45 of pivoted bag grippers at the outer end of said arm, a latch device for holding said member with said arm in position to deliver a bag, and actuating means for said latch arranged adjacent said grippers and adapted 50 to prevent the attachment of a bag there-

to until said means is moved so as to effect the actuation of said latch.

4. In a mail crane, the combination of vertically spaced relatively fixed bag supporting arms, a rotatable member on which 55 said arms are secured, a horizontally arranged plate secured to the outer end of the lower of said arms and adapted to form a seat for the bag, and means at the outer end of the upper of said arms for gripping the upper 60 part of the bag.

5. In a mail crane, the combination of vertically spaced relatively fixed bag supporting arms, a rotatable member on which 65 said arms are secured, a horizontally arranged plate secured at the outer end of the lower of said arms and adapted to form a seat for the bag, means on said plate for gripping the bag, and means at the outer end of the upper of said arms for gripping 70 the upper part of the bag.

6. In a mail crane, the combination of vertically spaced relatively fixed bag supporting arms, a rotatable member on which 75 said arms are secured, a horizontally arranged plate secured to the outer end of the lower of said arms and provided with a groove or depression adapted to receive the bag, and a spring pressed gripper device on said plate for gripping the bag to secure 80 it in position.

7. In a mail crane, the combination of a post, an inclined cam track surrounding said post, a member rotatably supported by said post and having means engaging said track, 85 bag supporting arms carried by said member, said track being so arranged that said means is in engagement with the upper part of the incline when said arms are in position to deliver a bag, and releasable means 90 independent of said track and within said member for locking the member to said post when the means is at the upper part of the track.

In testimony whereof I affix my signature 95 in presence of two witnesses.

ALBERT HUPP.
